Des. 205,641
Patented August 30, 1966

205,641

SAFE DEPOSIT BOX

Arthur T. Roth, Rockville Centre, N.Y., assignor to Franklin National Bank, Mineola, N.Y., a national banking association

Filed Nov. 2, 1965, Ser. No. 87,986

Term of patent 14 years

(Cl. D69—1)

FIG. 1

FIG. 2

FIG. 3

FIG. 4

FIG. 5

FIG. 6

FIG. 7

FIG. 1 is a perspective view of a safe deposit box showing my new design;

FIG. 2 is a front elevational view thereof;

FIG. 3 is an elevational view taken from one end thereof;

FIG. 4 is an elevational view taken from the end opposite that shown in FIG. 3;

FIG. 5 is a bottom plan view thereof;

FIG. 6 is a rear elevational view thereof;

FIG. 7 is another front elevational view thereof showing the box in an open position; and

FIG. 8 is a perspective view of the box in a further open position.

I claim:

The ornamental design for a safe deposit box, substantially as shown.
